[57] CLAIM

The ornamental design for an billiard glove, as shown and described.

DESCRIPTION

FIG. 1 is a front perspective view of a billiard glove showing my new design;

FIG. 2 is a rear perspective view thereof;

FIG. 3 is a left side elevational view thereof;

FIG. 4 is a bottom plan view thereof;

FIG. 5 is a right side elevational view thereof; and

FIG. 6 is a top plan view thereof.

The broken lines shown in the several views represent conventional stitching.

FIG. I

FIG. 2

FIG. 3

FIG. 4

FIG. 5
